UNITED STATES PATENT OFFICE

2,450,971

PATIENT TRANSFER CARRIAGE

Gerald C. Letch, Fort Sam Houston, Tex.

Application October 31, 1945, Serial No. 625,743

1 Claim. (Cl. 296—20)

1

The present invention relates to new and useful improvements in invalid or patient transfer carriages of a type used in hospitals or the like where sick, injured, or unconscious people are to be moved from one location to another, as from a bed to an operating table, or vice versa, and with a minimum of effort by attendants and in a manner to avoid further injury to the patient and to support the patient in a comfortable position after and while being moved.

An important object of the present invention is to provide a device of this character including a vertically adjustable platform having a laterally slideable top adapted to project in a direction toward either side of the platform into a position overlying a bed or other object on which a person may be lying whereby the person may be moved onto and off of the platform with a minimum of effort and discomfort to the person.

A further object of the invention is to provide safe operating mechanism for vertically adjusting the platform and to maintain the platform in vertically adjusted position without danger of accidentally being lowered after the weight of a person is placed thereon.

Another object of the invention is to provide a novel brake construction to prevent movement of the carriage during the transfer of the patient.

A still further object is to provide an apparatus of this character of simple and practical construction, which is strong and durable, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which:

Figure 1 is a side elevational view with parts broken away and shown in section.

Figure 2 is a horizontal sectional view taken substantially on a line 2—2 of Figure 1.

Figure 3 is a transverse sectional view taken substantially on a line 3—3 of Figure 1.

Figure 4 is a fragmentary top plan view of the platform.

Figure 5 is a fragmentary sectional view showing one of the racks and pinions taken substantially on a line 5—5 of Figure 1, and

Figure 6 is an enlarged side elevational view of one of the brakes for the carriage.

Referring now to the drawings in detail, where-

2

in, for the purpose of illustration, I have disclosed a preferred embodiment of the invention, the numeral 5 designates the carriage frame generally which includes lower, longitudinal and transverse frame members 6 and 7, respectively, connected to corner posts 8, said frame being constructed of tubular metal or other suitable inexpensive and strong material.

Wheels 9 are swivelly mounted at the lower ends of the posts 8 for moving the carriage from place to place.

An upper frame structure designated generally at 10 is carried by the corner post 8 and includes longitudinal, flat strips 11 and transverse, flat strips 12 connected at their ends to each other in any suitable manner outwardly of the post 8. Vertical bars 13 extend above and below the longitudinal strips 11 at each side of the carriage and are connected at their upper ends to a horizontal frame 14 which rests on top of the post 8.

Welded or otherwise suitably secured on top of the frame 14 adjacent its ends is a pair of transverse bars 15, each formed with a center guide opening 15a and having their outer edges 25 formed with an upwardly inclined flange 16 and on which a platform, designated generally at 17, is adapted to be seated.

The platform 17 includes an open frame 18 and end frames 19 extending downwardly therefrom and adapted for conformably positioning on the bars 15, as indicated in Figure 3 of the drawing.

The frame 18 is provided with a plurality of spaced, parallel guide rods 20 arranged transversely of the carriage and on which collars 21 are slidably mounted, the collars being welded or otherwise suitably secured to the underside and substantially equidistantly from the longitudinal side edges of a top 22 which is slidably supported on the upper edges of the frame 18 of the platform.

Secured to each of the end frame members 19 is a rack bar 23 which extends downwardly from the platform for sliding in the opening 15a and engaged by pinions 24 secured at the ends of a longitudinally extending shaft 25 journaled in bearings 26 carried by the transverse frame members 12.

A worm gear 27 is secured to the shaft 25 intermediate the ends thereof and engages a worm 28 secured at the center of a transverse shaft 29 which is journaled in the upper portion of the bars 13 at the opposite sides of the carriage and operated at either end by hand wheels 55 30. To the lower end of each of the side bars

13 is pivotally attached a ground-engaging brake 31 having rubber covering 32 secured to the upper and lower surfaces thereof, the brake being adapted for lowering into a position at either side of the carriage, as indicated in Figure 3 of the drawing, the rubber covering at the under side of the brake being adapted to frictionally engage a floor or other surface to prevent lateral as well as longitudinal movement of the carriage.

The brakes 31 are secured in a raised position by means of pivoted catches 33 secured to the bars 13.

In the operation of the device, the carriage is moved alongside a bed, operating table, or other object on which a person may be lying and the platform 17 vertically adjusted by the hand wheels 30 to position the frame 18 substantially in the horizontal plane of the bed or operating table.

The top 22 is then slidably moved laterally of the platform 17 into a position overlying the bed or operating table and a flexible, light-weight canvas sheet or other sheet of material is placed under the patient and on top of the top 22 of the platform. By pulling on the sheet, the patient is drawn onto the top 22 and the top 22 then slidably moved on the platform 17 to the center thereof. The platform 17 is then lowered into position for seating on the frame 15, as shown by the dotted lines in Figure 3 of the drawing.

While the platform 17 is in its elevated position, the worm gear 27 and worm 28 will prevent accidental lowering movement of the platform while the patient is being transferred thereto.

In view of the foregoing description taken in conjunction with the accompanying drawings, it is believed that a clear understanding of the construction, operation and advantages of the device will be quite apparent to those skilled in this art.

A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claim.

What I claim is:

- 10 An invalid transfer table comprising a carriage, a platform mounted for vertical adjustment on the carriage, spaced parallel, laterally extending guide rods carried by the platform, a top for the platform having collars on its under side slidably mounted on said rods for movement into and out of position overlying an object on which a person is lying for moving the person onto or off of the table, upper end cross bars on said carriage with upwardly inclined end flanges, and end frames on said platform conformably fitting against said bars when said platform is lowered.

GERALD C. LETCH.
